UNITED STATES PATENT OFFICE

95,767

DESIGN FOR A SANDAL OR SIMILAR ARTICLE

John C. Marks, New York, N. Y.

Application March 27, 1935, Serial No. 56,069

Term of patent 3½ years

To all whom it may concern:

Be it known that I, John C. Marks, a citizen of the United States, residing at New York, in the Borough of Manhattan, county and State of New York, have invented a new, original, and ornamental Design for a Sandal or Similar Article, of which the following is a specification, reference being had to the accompanying drawing, forming part thereof.

Fig. 1 is a perspective view of a sandal or similar article showing my new design, and

Fig. 2 is a rear elevation of the heel of said sandal or similar article.

The dominating feature of my design resides in the contour of the heel shown in full lines.

I claim:

The ornamental design for a sandal or similar article substantially as shown and described.

JOHN C. MARKS.
